UNITED STATES PATENT OFFICE.

FRANK FRANCIS TURNER, OF LITTLE FALLS, MINNESOTA.

HOT-WATER FURNACE.

1,218,133.

Specification of Letters Patent.

Patented Mar. 6, 1917.

Application filed November 1, 1915. Serial No. 59,094.

To all whom it may concern:

Be it known that I, FRANK F. TURNER, a citizen of the United States, residing at Little Falls, in the county of Morrison and 5 State of Minnesota, have invented certain new and useful Improvements in Hot-Water Furnaces, of which the following is a specification, reference being had to the accompanying drawings.

10 This invention relates to certain improvements in hot water furnaces and has for its primary object to provide means whereby the water may be heated to a high degree in its passage through the several water chambers of the furnace, with the consumption of a minimum amount of fuel.

The invention has for another of its objects to provide a furnace of the above type having a multiplicity of superposed water 20 chambers and fire flues alternately disposed with respect to the chambers and extending the entire length thereof.

It is an additional object of the invention to provide means for discharging the smoke 25 and products of combustion directly from the grate into the chimney flue when it is desired to clean the walls of the water chambers.

It is still another object of the invention 30 to provide a hot water furnace which is simple and economical in its construction and may be advantageously employed as a low pressure steam generator.

With the above and other objects in view, 35 my invention consists in the novel features of construction, combination and arrangement of parts to be hereinafter more fully described, claimed and illustrated in the accompanying drawing, in which,

40 Figure 1 is a vertical sectional view of a hot water furnace, illustrating the preferred embodiment of the invention;

Fig. 2 is a transverse vertical section;

Fig. 3 is a section taken on the line 3—3 45 of Fig. 1; and

Fig. 4 is a perspective view of one of the water chamber sections.

Referring in detail to the drawings, 5 50 designates the base of the furnace which is provided in its top surface, adjacent to its marginal edge, with a continuous groove or channel 6. In this channel, the lower edges of the shell or casing 7 of the furnace are seated and may be tightly secured therein by a suitable packing material. The front 55 wall of the furnace shell is provided with

the usual fire door, indicated at 8, and above the same with a pair of vertically spaced clean-out doors 9. 10 indicates the ash pit door. The rear wall of the shell 7 is provided with a vertically extending flue or passage 11 which leads to the chimney flue.

Upon the base 5, the walls of the ash pit 60 12 are suitably mounted or secured in spaced relation to the channel 6, and between the side walls of the ash pit the grate 13 is arranged. This grate may either be of the fixed or rocking type, but preferably the latter, and any preferred means may be provided for operating the grate sections.

Immediately above the grate, the main water chamber 14 is arranged, said chamber being of inverted U-shape form in cross-section and the side and top walls thereof having intercommunicating water spaces 15. 75 Above this main water chamber, the additional chamber sections 16 are arranged in superposed relation, said additional chambers being of somewhat less height than the main chamber 14. The top wall of this 80 chamber 14 is cut away or terminates short of the corresponding ends of the side walls of said chamber, as shown at 17, and the relatively opposite ends of the other water chambers 16 are also similarly cut away or recessed, as at 18. To the forward ends of the several water chambers, the vertical wall 19 is secured, said wall being provided with openings indicated at 20, which afford access to the fire passages between the several water chambers, to the fire box and to the ash pit. A vertical wall 21 is also secured to the rear ends of the several water chambers, and at its upper end this wall is recessed or cut away, as at 22, to a depth equal to the height 95 of the uppermost water chamber 16.

The side walls of the several water chambers are connected by spaced water conduits 23 which afford communication between the water spaces of the adjacent chambers. The space between the upper portions of the several superposed water chambers provides passages, indicated at 24, for the heat and products of combustion, the alternate passages communicating with the intermediate 100 passage at opposite ends of the furnace. There will thus be a travel of the smoke and products of combustion from the firebox throughout the length of the furnace, first upwardly and forwardly over the water chamber 14, and then rearwardly between the superposed chambers 16 to the chimney 105 110

flue. It will be observed that the walls of the water chambers are spaced from the corresponding walls of the outer furnace shell 7, and the air in this space also becomes 5 highly heated, thereby preventing chilling of the exterior walls of the several water chambers.

To the upper portion of the uppermost chamber 16 at its approximate center, the 10 hot water outlet pipe 25 is connected, and to each side of the main water chamber 14 a return pipe 26 is connected, said pipes leading in through the shell or casing 7, as will be readily understood. 27 designates the top 15 plate of the furnace shell which is securely fixed upon the upper edges of the walls of said shell or casing and is provided with an opening to accommodate the pipe 25. This top plate 27 also has an opening therein at 20 its rear end in communication with the smoke passage or outlet at the rear end of the furnace, and to the same a pipe leading to the chimney flue is adapted to be connected.

25 The rear wall 21 is provided with a plurality of spaced openings which are in communication with the firebox of the furnace, and a valve plate 28 is mounted upon the wall 21 in suitable guides 29 for sliding 30 movement over these openings. This plate may be actuated by a bar or rod, indicated at 30, which is connected thereto, and extends laterally from the plate and through an opening provided in one of the side walls 35 of the shell or casing 7. The plate 28 is adapted to be moved over the openings in the wall 21. Thus, the smoke and products of combustion may either be admitted directly from the firebox into the outlet flue, 40 or such communication cut off and the products of combustion caused to travel through the passages 24 in the manner above stated.

From the foregoing description, taken in connection with the accompanying drawings, the construction and manner of operation of the invention will be clearly and 45 fully understood. The cold water enters the water space in the main chamber 14 through the return pipes which are connected to the 50 radiators, and this water is first heated very quickly in this chamber by contact with the highly heated walls thereof. The heated water rises through the water legs 23 to the next water chamber 16, and finally from this 55 chamber into the uppermost chamber 16. The walls of these chambers are, of course, very highly heated by the passage of the products of combustion upwardly between the same so that the temperature of the 60 water will be increased to a very high degree when it leaves the uppermost chamber 16 and enters the outlet pipe 25 which carries the water to the radiators in the building. The circulation of the water in this 65 manner is continuous, and as the passages

24 for the smoke and products of combustion extend throughout the length of the furnace, it will be manifest that every portion of the inner walls of the chamber sections will transmit heat to the water in its 70 passage through the several water spaces. It is thus apparent that the furnace may be economically operated, and the water heated to a high temperature with a consumption of a relatively small amount of fuel. Upon 75 the opposite sides of the water chambers and the ash pit, the plates 32 are secured having openings to accommodate the return pipes and the water conduits. Over the latter openings, the cover plates 33 are arranged and secured by means of suitable fastening screws to the face of the plate 32.

In addition to the use of the invention as a water heater for the purpose of supplying hot water in heating systems, the furnace 80 can also be advantageously used as a low pressure steam generator if desired, as will be manifest from the foregoing description.

When it is necessary to clean the walls of the several water chambers defining the passages 25 for the smoke and products of combustion, the sliding valve plate 28 is moved to its open position so that the smoke will enter directly into the vertical flue or passage at the rear of the furnace and be conducted to the chimney flue and not travel through the passages 24. Thus, the walls of these passages may be scraped or otherwise cleaned through the clean-out doors in the front wall of the furnace shell, and the operator will suffer no inconvenience due to 95 smoke issuing from said passages.

In practice, it will be obvious that any desired number of the superposed water chambers may be employed, in accordance 100 with the desired heating capacity of the furnace. I also reserve the privilege of adopting various modifications in the form, proportion and arrangement of the several 105 structural features of the furnace, as may be fairly embodied within the spirit and scope 110 of the invention as claimed.

Having thus fully described my invention, what I desire to claim and secure by Letters 115 Patent is:—

The combination with a furnace body including front and rear walls, a rear vertical outlet flue and clean-out openings in the front wall, of a vertical tier of superposed water chambers of inverted U-shaped form 120 the side walls of which are unconnected at their ends and abut against the front and rear walls of the furnace body, conduits connecting each of the side walls of adjacent water chambers to each other at their opposite ends, the top walls of adjacent chambers being cut away at their relatively opposite ends between the side walls of the chamber to afford communication between the longitudinal flues for the products of combustion, 125 130

the rear wall of the furnace body being provided in its upper end with an opening affording communication between the cut-away portion of the uppermost water chamber and the outlet flue, said wall being also provided with a series of vertically disposed openings extending above and below the horizontal wall of the lower water chamber and affording communication between the 10 fire box and the next adjacent longitudinal

flue and said outlet flue, and means for cutting off or establishing such communication with the outlet flue.

In testimony whereof I hereunto affix my signature in the presence of two witnesses. 15

FRANK FRANCIS TURNER.
